Primary Examiner — George D. Kirschbaum*Assistant Examiner* — Joseph J Kukella(74) *Attorney, Agent, or Firm* — Grace J. Fishel(57) **CLAIM**

The ornamental design for a toss game playing piece and rod, as shown and described.

DESCRIPTION

FIG. 1 is a perspective view of a toss game playing piece and rod showing my new design;

FIG. 2 is a top plan view thereof, the bottom plan view being a mirror image;

FIG. 3 is a rear view thereof;

FIG. 4 is a front view thereof; and,

FIG. 5 is a right side view thereof, the left side view thereof being a mirror image.

The broken lines in the drawings are directed to portions of the toss game playing piece and rod that form no part of the claimed design.

1 Claim, 3 Drawing Sheets(56)
